UNITED STATES PATENT OFFICE.

CHARLES HENRY WACHOLZ, OF SANTA CLARA, CALIFORNIA.

GUARD FOR WOODWORKING-MACHINES.

1,160,219.

Specification of Letters Patent. Patented Nov. 16, 1915.

Application filed August 2, 1915. Serial No. 43,167.

To all whom it may concern:

Be it known that I, CHARLES HENRY WACHOLZ, a citizen of the United States, residing at Santa Clara, in the county of 5 Santa Clara and State of California, have invented a new and useful Guard for Woodworking-Machines; and I do hereby declare the following to be a full, clear, and exact 10 description of the invention, such as will enable others skilled in the art to which it 15 pertains to make and use the same.

This invention relates to an improved 20 guard for a wood working machine having a vertical cutter head rising from the table 25 of the machine, and an object of the invention is to provide a device of this design to protect the fingers and hands of the operator 30 against accidentally coming in contact with the blades of the cutter head.

Another object of the invention is to provide 35 a guard involving improved features of construction.

One of the features of construction is the 40 provision of a standard, to which an arm has universal connections, at the free end 45 of which arm a holder is connected, to which in turn the sleeve is adjustably fixed, said 50 sleeve having a cage constituting a guard to protect the fingers and hands of the operator 55 against accidental injury by the blades of the cutter head.

In practical fields the details of construction 60 may necessitate alterations, falling within the scope of what is claimed.

The invention comprises further features 65 and combination of parts, as hereinafter set forth, shown in the drawings and claimed.

In the drawings:—Figure 1 is a view in 70 perspective of the improved guard constructed in accordance with the features of the invention. Fig. 2 is a vertical sectional view, showing parts in elevation. Fig. 3 is a sectional view on line 3—3 of Fig. 2. Fig. 4 is a sectional view on line 4—4 of Fig. 2.

Referring to the drawings, 1 designates 75 the bed plate of a wood working machine (not shown), and to which plate a plate 2 having dove-tailed guide flanges 3 is bolted, as shown at 4. Mounted in the guide flanges, 80 is a standard or frame 5, which may be held in adjusted positions in the guides by the set bolts 6. Secured at 7 to the top of the frame or standard is the base plate 8 of a semi-cylindrical bearing member 9, which 85 receives the sleeve 10, there being a screw 11

to hold the sleeve 10 in adjusted position in the bearing. A pin 12 extends through the bearing and through the sleeve, there being a collar 13 secured on the pin by the set bolt or screw 14, thereby pivotally 60 mounting the sleeve in the bearing. The collar 13 holds the pin against passing entirely through the bearing and the sleeve, in other words, prevents the pin from falling out. The sleeve 10 has a lateral portion 15, 65 which is bifurcated, as shown at 16. An ear 17 of the arm 18 is pivoted in the bifurcation 16 by the pivot pin 19. The interengaging shoulder 20 and 21 of the arm 18 and the lateral projection 16 constitute means 70 to hold the arm in the positions shown in Figs. 1 and 2. However, it will be observed the arm is free to move upwardly a short distance. The free end of the arm has a sleeve bearing 22, in which a pin 23 is 75 mounted, there being a split collar 24 having a set screw 25 for holding the pin 23 in the sleeve bearing. Threaded to the lower end of the pin 23 is a cylindrical part 26 of the spider plate 27, the arms 28 of which 80 are bolted or otherwise secured at 29 to the cylinder or sleeve 30.

The cylinder 30 is provided with a rib 31 having ratchet teeth 32. The rib 31 extends or fits into a groove 33 of the inner circumference of the sleeve 34, which telescopes the cylinder 30. The sleeve 34 has a lateral hollow projection 35, in which a spring tensioned pin 36 is mounted, the nose 37 of which engages any one of the ratchet teeth 32 of the rib 31, to hold the sleeve 34 in adjusted positions upon the cylinder 30. It will be observed that the rib prevents rotation of the sleeve 34, and also that the sleeve by simply pushing upwardly upon the same 95 may be raised upon the cylinder 30, but by means of the ratchet teeth being engaged by the pin 36 the sleeve 34 is prevented in its downward movement. However, the pin 36 may be pulled out of engagement with the 100 ratchet teeth by the finger of the operator, so that the sleeve 34 may be lowered.

A guard 38 to prevent the fingers and hands of the operator from coming in contact with the blades of the cutter head of 105 the wood working machine (not shown) is provided. This guard is in the form of a cage, consisting of the upper and lower rings 39 and 40, connected by the rods 41. The guard or cage is secured to the sleeve 34, by 110

the set bolts or screws 42, which are threaded through the upper ring 39. It will be noted that the cage or guard may be adjusted very close to the bed plate, and in such wise as to leave but a slight space between the lower edge of the guard and the bed plate, to permit a piece of timber or board or the like, of about a sixteenth of an inch to be inserted between the lower edge of the cage or guard and the bed plate to be operated upon by the blades of the cutter head, and owing to the guard being in the form of a cage, or in the form of a skeleton frame, the operator is allowed full view as to the work being performed.

The invention having been set forth, what is claimed as new and useful is:—

1. In combination, a standard, an arm having universal connections with the upper portion of the standard, a cylinder suspended from the free end of the arm, a sleeve telescopically mounted upon the cylinder and having a guard connected to its lower part, means for guiding the sleeve on the cylinder,

and means for holding the sleeve in adjusted position on the cylinder.

2. In combination, a standard, an arm having universal connections with the upper portion of the standard, a cylinder suspended from the free end of the arm, a sleeve telescopically mounted upon the cylinder and having a guard connected to its lower part, the inner circumference of the sleeve having a groove, the cylinder having a rib provided with ratchet teeth fitting the groove to guide the sleeve when adjusted vertically, and a spring tensioned pin mounted in the wall of the sleeve for engaging the teeth for holding the sleeve in vertical adjusted positions on the cylinder.

In testimony whereof I have signed my name to this specification in the presence of two subscribing witnesses.

CHARLES HENRY WACHOLZ.
